UNITED STATES PATENT OFFICE.

LARRY G. BONDURANT, OF HANNIBAL, MISSOURI.

SANITARY CALORIC-BATH APPARATUS.

1,192,740.

Specification of Letters Patent. Patented July 25, 1916.

Application filed January 7, 1916. Serial No. 70,820.

To all whom it may concern:

Be it known that I, LARRY G. BONDURANT, a citizen of the United States, residing at Hannibal, in the county of Marion, 5 State of Missouri, have invented a new and useful Sanitary Caloric-Bath Apparatus; and I do hereby declare the following to be a full, clear, and exact description of the invention, such as will enable others skilled 10 in the art to which it appertains to make and use the same.

This invention relates to an improved apparatus, whereby caloric baths may be administered to persons for curative purposes.

15 One of the objects of the invention is to provide an apparatus or cabinet, in which the patient may be arranged, for the purpose of sweating the impurities from the body by heat, for purifying the various tissues of the body. In other words, the impurities are thrown off by sweating, for benefiting the patient.

In practical fields the details of construction may necessitate alterations, falling 20 within the scope of what is claimed.

The invention comprises further features and combination of parts, as hereinafter set forth, shown in the drawings and claimed.

In the drawings: Figure 1 is a vertical 25 sectional view of the improved caloric bath cabinet constructed in accordance with the invention, showing the various features of construction, and the thermostatic means for controlling the heat in the cabinet, and the 30 means for deflecting the heat against the radiating surface of the bottom of a cabinet. Fig. 2 is a sectional view transversely of Fig. 4 on line 5—5. Fig. 3 is a top plan view of the cabinet.

40 Referring more especially to the drawings, 1 designates a base frame, which in the present instance is rectangular in contour or shape, and which may be constructed of any suitable metal preferably galvanized iron 45 heavily enameled, or constructed of aluminum. This base frame is provided with supporting legs 2 at the corners, the lower ends of which are connected by longitudinal and transverse bars 3 and 4. The top of this 50 base frame is constructed from a single sheet, and is provided with a four sided tapering depression 6 terminating in a horizontal flat bottom 7. This tapering depression constitutes a radiating surface for the heat, in 55 order that it may be radiated, so as to circ-

culate on the interior of the cabinet. The flat bottom portion 7 is provided with a central opening 8, which is flanged above as at 9 and flanged below as at 10. Rising from the flange 9 are the supporting legs 11, which 60 are integrally connected to the conical deflector 12, which deflects the heat subsequently to passing through the opening 8, against the interior of the depression 6, which radiates and deflects the heat into the 65 interior of the cabinet. The heat is generated from any suitable heater. The flat bottom portion 7 is provided with a semi-circular slit or opening 13, and that portion 14 of the metal of the bottom 7 adjacent the slit 70 or opening 13 is slightly depressed, and is provided with a gulley or trough 14 to carry off all exudations, which exudations and the like may empty into a receptacle (not shown), which may be arranged under and 75 adjacent the opening or slit 13.

Each end of the depression 6 is provided with a shouldered part 15. Engaging the shouldered part or raised portion 15 is a slab 16 which may be constructed of galvanized sheet iron or the like heavily enameled, and which is provided with elongated alternately arranged bars and openings 17 and 18. The bars 17 have their edge portions deflected or rounded downwardly, so as to 80 prevent injuring the body, while the opening 18 constitutes means to permit the heat to pass upwardly into the cabinet. By virtue of the shoulders 19 adjacent the part 15, endwise movement of the slab 16 is prevented. The cabinet 20 in the present instance comprises an arched hood, which is hinged at 21 adjacent one of the longitudinal side portions or edges of the top of the base frame of the cabinet. The arched 85 cabinet or hood adjacent its edge opposite the hinges 21 is provided with a hand grip 22, whereby the cabinet or hood may be raised, to permit the person to enter, in order to lie upon the slab. One end of the 90 arched cabinet or hood adjacent its lower edge is provided with an opening 24 through which the neck of the person extends. Secured to the upper face of the top at one end of the base frame is a head and neck 95 supporting plate 25, which is curved and shaped as to fit the back part of the neck and the head of a person. On one end of the arched cabinet or hood adjacent the opening 24 is a pair of hooks 26, adapted to be en- 100 105 110

gaged by a suitable towel or the like (which rests on a rubber pillow), to assist in supporting the head and easing or relieving the strain incident to the pillow being supported on the plate 25. The top of the arched cabinet or hood substantially centrally thereof is provided with an opening 27 which is closed by the slide 28, mounted in the guides 29. By opening the slide 28 excessive heat 10 may quickly escape, without waiting for the automatically controlled damper 29 to open. The damper 29 covers an opening 30 in the top of the arched cabinet or hood, and is carried by a pivoted arm or lever 31, pivoted 15 at 32 to a lug 33. Fixed to the inner face of the top of the arched cabinet or hood is a hook arm or bracket 34, which supports a thermostatic device 35, the side portion 36 of which has connected to it a link 37, which 20 in turn is pivoted at 38 to the lever or arm 31. It is to be noted that as the heat in the cabinet or hood varies, the thermostatic device 35 will contract and expand, thereby moving the arm or lever 31 upon its pivot, 25 and causing the damper 29 to raise and lower, to open and close said damper 29, whereby the heat in the cabinet is automatically controlled. As clearly shown in Fig. 2 one side of the arched cabinet or hood 30 is provided with a sight opening 40, which is covered by any suitable transparent material 41. In other words, by virtue of this opening an attendant may see into the cabinet, not only to ascertain the condition of 35 the body of the patient, but may also ascertain the temperature of the heat, which

will be given by the thermometer 42, which is arranged adjacent the sight opening.

The invention having been set forth, what is claimed as new and useful is:

In a caloric bath apparatus, the combination of a base frame having a top sheet provided with a conical depression and an arched cabinet hood to arch over the body of a person and being hinged to the top 45 sheet and having an opening in one end to receive the neck of the body, of a slab resting upon the top sheet directly over said depression and provided with a plurality of elongated openings, said depression having a flat portion near the termination of the conical part thereof, said flat portion having a circular opening and provided with a flange rising upwardly and surrounding the opening, a conical deflector rising from and 50 being integral with said flange and spaced thereabove, to deflect the heat against the upper surface of said depression of the top sheet, where the heat radiates toward and against the body, said flat portion of the 55 depression having a small depression provided with an outlet, for carrying off the exudations, the ends of the first depression having shouldered parts to support the slab, and means to support the head of the body. 60

In testimony whereof I have signed my name to this specification in the presence of two subscribing witnesses.

LARRY G. BONDURANT.
